UNITED STATES PATENT OFFICE.

JOSEPH J. HALL, OF CHICAGO, ILLINOIS, ASSIGNOR TO HALL'S AUTOMATIC FEED BOILER FURNACE COMPANY, OF SAME PLACE.

BOILER-FURNACE.

SPECIFICATION forming part of Letters Patent No. 294,998, dated March 11, 1884.

Application filed August 13, 1883. (No model.)

To all whom it may concern:

Be it known that I, JOSEPH J. HALL, residing at Chicago, in the county of Cook and State of Illinois, have invented certain new and useful Improvements in Boiler-Furnaces, of which the following, in connection with the accompanying drawings, is a specification.

In the drawings, Figure 1 is a front view of a furnace embodying my invention. Fig. 2 is a vertical cross-section of the forward part of the furnace. Fig. 3 is a section in the plane of the line xx , Fig. 2. Fig. 4 is a detail, the same being a side view of a portion of the stoker; and Fig. 5 is a vertical cross-section 15 through the same.

Like letters of reference indicate like parts.

A A represent the furnace-walls, and B is the boiler. C C are the retorts; D, the grate; and E is the ash-pit. F is the coking-oven. 20 G is the flame-chamber, and a a are passages through which it communicates with the retorts.

It will be perceived that the coking-oven and retorts are located in front of the boiler. 25 It will also be perceived that I employ two retorts, separated, excepting as hereinafter explained, by a longitudinal wall, b, and that the coking-oven communicates with both retorts. These two retorts I employ in the example shown in connection with a single boiler; but the principal features of my present invention relate to the means employed for breaking up the coke and feeding it into the retorts, or depositing it upon the fire, and 30 also to the means employed for supplying the retorts with air or oxygen. The bottom c of the coking-oven rests upon the wall b, and is slightly arched, by preference, as shown.

The side walls, c' c', are by preference somewhat flaring, as shown, being farthest apart at their lower edges. Between the lower edges of the walls c' c' and the longitudinal edges of the bottom c are openings or spaces d d. In other words, these edges do not meet, and the 45 coking-oven is so set into the furnace-walls that one opening d enters one of the retorts, and the other opening enters the other retort. e e are the ends of the retort. F' F' are the doors of the coking-oven. I deem it best to 50 employ two doors, as shown, and to hinge one

door to one side and the other to the other side of the coking-oven, the doors being so arranged that one will overlap the other when closed. These doors, when open, I support in inclined positions, as indicated by the dotted lines at f f of Fig. 2, so that they will serve as a hopper. 55

H is the breaker and stoker. This stoker consists of a shaft, g, having bearings in the front and rear ends of the coking-chamber, 60 and in the front wall or arch of the furnace, as is clearly indicated in Fig. 3.

I I are fingers or crushers projecting from that part of the shaft g which is within the coking-oven. I deem it best to make these 65 fingers polygonal, as represented, and to arrange the corners or edges so that they will aid in breaking or crushing the coke when the shaft g is rotated or rocked for that purpose, as will hereinafter more fully be explained. I also deem it preferable to make the fingers I I of different lengths, the longer ones alternating with the shorter, as shown in Figs. 3 and 4. 70

J is a lever or handle on the outer or exposed end of the shaft g. 75

K is an air space or chamber extending across the front wall of the furnace, and extending over the top of the furnace to and around the coking-oven, and thence along the 80 sides and front and rear of the said oven, as indicated in Figs. 2 and 3. The lower front part of this chamber enters the ash-pit, and that part of the said chamber which surrounds the sides and ends of the coking-oven enters 85 the retorts C C.

L L are doors opening into the ash-pit, and L' L' are doors opening into the retorts. These doors may be perforated, as shown at h h, to permit air to pass from the chamber K 90 into the retorts. M is a shaker for shaking the grate D.

In order to apply my improvements to use for the purposes for which they are intended, I proceed as follows: A fire being built in the 95 retorts in the usual manner, I supply it thereafter with fuel by filling the cooking-oven with soft coal, the doors of the oven being opened and allowed to remain open while the furnace is in use. I also open either the doors L L or 100

the dampers therein, in order to supply the draft and air required to sustain combustion and produce the required degree of heat. While the fuel in the retort is being consumed, the 5 coal in the coking-oven, or at least the lower portion thereof, becomes coked, and in becoming coked swells out and clogs the openings *d d*, the coke and coal in the coking-oven being thus suspended therein, but still subjected to 10 the high heat in the retorts. When more fuel is to be supplied to the incandescent or burning mass in the retorts, I vibrate or rock the lever *J* sufficiently to break up the mass of coke suspended in the openings *d d*, and this broken 15 coke then falls into the retorts, and is also pushed out of the coking-oven into the retorts, as well as broken by the fingers *I I*, while the shaft *g* is rocked or rotated in the manner described. The uncoked coal in the coking-oven 20 or its hopper then falls down, and in turn becomes coked, the intention being not to allow the coking-oven or hopper to become empty while the furnace is in use. The doors *F' F'*, however, may be closed when it may be de- 25 sired to allow the fire to burn out, or when the furnace is not in use. The air, in entering through the doors *L L*, not only passes through the grate, as usual, but also distributes itself 30 through the chamber *K*, becomes heated to a greater or less degree, and passes into the retorts, thereby supplying those chambers with a sufficient supply of oxygen to sustain combustion. The gases escaping from the retorts pass through the openings or passages *aa* into 35 the chamber *G*, where the flames and heated air produce a high degree of heat underneath the boiler, and from thence the heat passes through the boiler-flues and out in the usual manner, thus generating steam in the boiler. 40 It will be perceived from the foregoing description and from reference to the drawings that no doors need be opened for the purpose of stoking, and hence that the fire will not be deadened by the entrance of a large volume of 45 cold air. It will also be perceived that the fuel is coked before it is fed to the incandescent mass in the retorts, and hence that it is better prepared for combustion without producing those fine and fleecy particles of carbon which escape without being consumed, and 50

which are commonly designated as "smoke." It will also be perceived that the combustion will in all respects be more perfect or complete than in furnaces adapted to be fed or stoked in the usual manner. I also desire to 55 call attention to the fact that the air-chamber *K*, besides supplying oxygen to the burning fuel, serves to protect the plates of the coking-oven from the effects of the intense heat produced, the said chamber performing the 60 function also of a cooling-jacket, especially about those parts most exposed to heat.

A battery of two or more boilers may be stoked simultaneously, either by hand or by power, by connecting the levers *J J*, operating 65 in connection with each stoker, and by actuating any one of the said levers.

Having thus described my invention, what I claim as new, and desire to secure by Letters Patent, is—

70

1. The combination, in a furnace, of the coking-oven *F*, the retorts *C C*, and the rocking breaker and stoker centrally pivoted, the said coking-oven opening into the said retorts, and all arranged substantially as shown and 75 described with relation to each other, for the purposes set forth.

2. The combination, in a furnace, of the coking-oven *F*, the retorts *C C*, and a stoker and breaker centrally pivoted in the said cok- 8c ing-chamber, and consisting of the rocking shaft *g*, having thereon the fingers *I I*, and provided with an actuating lever or handle, substantially as and for the purposes set forth.

3. The combination, in a furnace, of the 85 coking-oven *F*, the retorts *C C*, and an air-chamber, *K*, the latter extending from the ash-pit up the front of the furnace, thence over the front wall, and thence around the sides and ends of the coking-oven, and entering the 90 said retorts, substantially as and for the purposes specified.

In testimony that I claim the foregoing as my own I here affix my signature in presence of two witnesses.

JOSEPH J. HALL.
